UNITED STATES PATENT OFFICE.

FRANCIS STANLEY LOWE, OF HENLEY-ON-THAMES, ENGLAND.

ROWLOCK.

SPECIFICATION forming part of Letters Patent No. 710,873, dated October 7, 1902.

Application filed June 19, 1902. Serial No. 112,342. (No model.)

To all whom it may concern:

Be it known that I, FRANCIS STANLEY LOWE, a citizen of England, residing at Orchard, Shiplake, Henley-on-Thames, England, have 5 invented a certain new and useful Improvement in Rowlocks, of which the following is a specification.

My invention relates to a construction of rowlock specially adapted for use on wagger- 10 boats having outriggers, my object being to provide a stable abutment for the oar, yet allowing sufficient freedom for its movements in rowing, as I shall describe, referring to the accompanying drawings.

15 Figure 1 is a side view of a rowlock according to my invention. Fig. 2 is a plan on the top, and Fig. 3 is a sectional plan on the line 3 3 of Fig. 1.

20 *a* is a base which can be secured by bolts *b* on the end of the outrigger of a wagger-boat or on a plate fixed on the gunwale of an ordinary boat. From the base *a* project two arms, constituting a frame, in the form of an *L*, the upright arm *c* being of **V** transverse section, with a lip *d* projecting forward at its top. The horizontal arm *e* tapers to a less thickness at its front end. Both limbs have 25 fixed to them in any suitable manner linings *f g*, of wood or equivalent material, that will not damage the oar moving against and on the linings. Another *L*-shaped piece has its horizontal limb *h* pivoted on the base *a* at *i*, and its upright limb *k* has at its top a lip *l* projecting backward and having through it 30 a round hole notched at one side. On the projecting part *d* is pivoted at *m* a cover-bar *n*, having at its front end a screw *p*, projecting upward, fitted with a nut *q*, made with a milled head, so that it can be turned by the

finger and thumb. For this a fly-nut might 40 obviously be substituted. By unscrewing the nut *q* as far as is permitted by the bur end of the screw *p* the bar *n* can be swung back on its pivot *m*, so as to admit the oar in the angle of *f* and *g*, and then the bar *n* can be 45 swung forward over the oar, so as to prevent it from coming out of the rowlock, the screw *p* passing through the notch of the hole in *l* and then being secured by screwing down the nut *q*. 50

In rowing the oar rests on the lining *g* and abuts against the lining *f*, (which, preferably, is a little rounded at its edges,) and when the front face of the oar comes against the limb *k* it causes the *L*-piece *k h* to swing a little 55 on its pivot *i*, its swing being limited by flat faces *r* at the rear end of its horizontal limb.

Having thus described the nature of this invention and the best means I know of carrying the same into practical effect, I claim— 60

A rowlock comprising a base from which projects an *L*-shaped frame having its limbs lined with wood the said base being fixed on an outrigger or gunwale, another *L*-piece having its horizontal limb pivoted on the base, 65 and the top of its upright limb fitted to receive a fastening of one end of a covering-bar the other end of which is pivoted on the top of the vertical limb of the *L*-frame, substantially as described. 70

In testimony whereof I have hereunto set my hand in presence of two subscribing witnesses.

FRANCIS STANLEY LOWE.
